RAILWAY TRAFFIC CONTROLLING APPARATUS

Original Filed July 23, 1930 2 Sheets-Sheet 2

UNITED STATES PATENT OFFICE

RALPH R. KEMMERER, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY TRAFFIC CONTROLLING APPARATUS

Application filed July 23, 1930, Serial No. 439,941. Renewed February 26, 1932.

My invention relates to railway traffic controlling apparatus for governing traffic over a stretch of railway wherein there is located a switch, and more especially it relates to that class of apparatus whereby a despatcher or operator, located in a central office, controls the movements of the switch and the signals associated therewith.

In systems where an operator located at some remote point controls the movement of a railway switch and its associated signals, it is customary to provide approach locking circuits, and to provide also means to check the integrity of the approach locking circuits. In approach locking provided heretofore, a momentary loss of shunt in an approach track circuit or a momentary short-circuiting of a detector track circuit may result in a loss of the approach locking, and such a loss will permit a switch to be reversed or to start to reverse in front of an approaching train.

In a despatcher control system, it is desirable to permit a route to be set up and the signals cleared, and to permit the despatcher to select a reverse control circuit for a switch which will reverse the switch immediately after a train has accepted the signals of the first route and cleared the detector track circuit. Such requirement makes it very desirable to provide a continuous check on the approach locking to insure that the switch does not prematurely operate. It is the purpose of my invention to provide a continuous check on the approach locking circuit and thereby prevent the loss of approach locking from occurring, and reduce to a minimum the possibility of a false operation of a switch.

I will describe one form of apparatus embodying my invention, and will then point out the novel features thereof in claims.

Figs. 1 and 2, when placed end to end, with the Fig. 1 to the left, form a diagrammatic view of the apparatus embodying my invention when used in connection with the operation of a single switch and its associated signals.

Referring to the drawings, a railway switch, designated by the reference charac-

ter SW, is operated by a standard type of switch machine, shown in the Fig. 2, by a symbol and designated by the reference character SM. The operating circuits for the switch machine SM are not shown in the figure inasmuch as they form no part of my invention and may be any one of several well known in the art. In this instance, the control of the switch machine SM is by means of despatcher controlled code relays to be referred to later.

By means of insulated rail joints 3, the track rails 1 and 2 are divided into track sections L3T, L2T, 1T, R2T and R3T. The track sections L3T, L2T, R2T and R3T will be referred to as approach sections, while the section 1T will be referred to as a detector track section. Each track section is provided with a customary track circuit which includes a track battery and a track relay in a manner readily understood from the drawings. The wayside signals that govern traffic over the switch SW from the right to the left are designated by the reference character L, plus a numeral to indicate the location, and the wayside signals governing traffic from the left to the right are designated by the reference character R, plus a numeral to designate the location. Inasmuch as the operating circuits of the signals form no part of my invention, they are all omitted from the figures for the sake of clearness. It is thought that they would add nothing to the understanding of my invention, and that it is sufficient to say that the signals R3 and L3 are three-position signals, each capable of displaying "proceed", "caution" and "stop", that the signals R2a and L2a are two-position signals, each capable of displaying "proceed" and "stop", that the signals R2d and L2b are two-position signals capable of displaying "caution" or "stop", that the signals R2c and L2c are "call-on" signals, and that the signal R2b is a fixed signal displaying "stop" only.

In order to simplify the figures somewhat and to make them easier to understand, I have, in a number of instances, placed a circuit controlling armature in a location that is not adjacent to the relay that controls the armature. In all such instances the armature

- is designated by a reference character with an exponent corresponding to the reference character of the controlling relay and all such armatures are shown in their normal positions. For illustration, the circuit controlling armature, designated by the reference character 88^{LM} in the Fig. 1, is controlled by the relay LM of Fig. 2, and the armature normally occupies its raised position.
- 10 The despatcher controlled relays are shown in Fig. 2 located on a panel indicated by a dotted line FS. As the circuits for the control of these despatcher controlled relays also form no part of my invention, they are not shown on the figures, it being understood, however, that the despatcher can elect to energize or deenergize these relays at will, and that whenever a relay is energized, it lifts its armatures, and when deenergized, its armatures drop to a down position. As a matter of fact, my invention is not limited to a despatcher controlled system for the control of the switch, it being equally adaptable to remote controlled systems or to power interlocking systems.

The circuit controllers 4, 5 and 6 of Fig. 2 are operated by the switch SW as indicated by a dotted line. Each controller occupies an upper position indicated by a solid line when the switch is set for the main track, while each controller occupies a down position indicated by a dotted line when the switch SW is set for a traffic movement to the siding.

The switch control relay W is a direct current polarized relay having polar armatures that remain in the position to which they were last moved by the energizing of the relay. This relay W, when energized with current of normal polarity, moves its polar armatures to a normal position that selects the operating circuits (not shown) for the switch machine SM that results in the switch SW being positioned for traffic on the main line. With current of reverse polarity supplied to the relay W, then the polar armatures are moved to a reverse position that selects the operating circuits for SM that result in the switch SW being positioned for traffic to the siding. In Fig. 2, the normal position of the polar armatures of the relay W is left-hand, as shown in the figure, and the reverse position is the right-hand position, that is, opposite from that shown in the figure. The switch control relay W is controlled by despatcher controlled relays RWS and NWS. With normal relay NWS selected by the despatcher, and its armatures 9 and 10 raised, current is supplied to the relay W by a circuit extending from battery terminal B along wire 11, armature 9, wire 12, relay W, wire 13, armature 14^{RM} controlled by a relay RM of Fig. 1 and referred to later, wire 15, armature 16^{LM} controlled by a relay LM, wire 17, armature 18 of the track relay TR, wire 19, armature 10, and wire 20 to common battery terminal C. The

polarity of the current thus supplied moves the polar armatures of relay W to the left-hand side and thus brings about the normal positioning of the switch SW. With the despatcher selecting the reverse relay RWS, current is supplied to the relay W from battery terminal B along wires 11 and 21, armature 22, wire 23, armature 10 of relay NWS in a down position, wire 19, armature 18, wire 17, armature 16^{LM}, wire 15, armature 14^{RM}, wire 13, relay W, wire 12, armature 9 in a down position, wire 24, armature 25, and wire 20 to common battery terminal C. The flow of current to relay W this time is reversed and the polar armatures reversed to the right-hand position with the result that the switch SW is set for traffic to the siding.

The switch controlled relay KR is a direct current polarized relay and is controlled jointly by the switch SW and the relay W. With the switch set in the normal position, and relay W also in the normal position, the circuit to the relay KR consists of battery terminal B, wire 26, controller 4, wire 27, relay KR, wire 28, armature 8, wire 29, controller 6, and wire 30 to common battery terminal C. With the switch SW and relay W each in reverse position, then the relay KR is supplied with current from battery terminal B along wires 26 and 31, controller 5, wire 32, armature 8, wire 28, relay KR, wire 27, controller 4, and wires 33 and 30 to common battery terminal C. With the relay KR energized coincidentally with the normal position of the switch SW and relay W, its neutral armatures are raised and its polar armatures occupy the left-hand position, while with the relay KR energized with the switch SW and relay W in reverse position, the neutral armatures of KR are raised and the polar armatures occupy the right-hand position.

The repeater relays NP and RP are controlled jointly by the relays KR and W. The circuit for the normal repeater relay NP extends from battery terminal B along armature 7, wire 34, armature 35, polar armature 36, wire 37, armature 38, wire 39, relay NP, and to common battery terminal C. The circuit for energizing the reverse repeater relay RP extends from battery terminal B along armature 7 in a right-hand position, wire 40, armature 41, polar armature 42 in a right-hand position, wire 43, armature 44 in a down position, wire 45, relay RP, and to common battery terminal C.

The direction of traffic over the switch SW is selected by the directional relays RH and LH, respectively. With the switch set for main line traffic and the despatcher selecting the relays RHS and XS on the panel FS, we find that current is supplied from battery terminal B to the relay RH over a circuit consisting of wires 11, 21 and 46, armature 47 of a relay LHS, wire 48, armature 49 of relay RHS in its raised position, wire 50, armature

51^{LH} of the directional relay LH, wire 52, coil of relay RH, wire 53, armature 54^{TR} of the relay TR, wire 55, armature 55^{NP} of the repeater relay NP, wire 56, armature 57 of the relay XS in its raised position, wire 58, armature 59 of the relay YS, and wires 60 and 20 to common battery terminal C. Once the relay RH is energized, there is a path to common battery terminal branching from the wire 55, along wire 61, armature 62^{KR}, wire 63, armature 64 of the relay RH, and to common battery terminal C. In the event the despatcher selects the relay LHS, while the relay NWS is energized to set the switch for the main line, relay XS is also energized, and we find that current will flow to the directional relay LH from battery terminal B, along wires 11, 21 and 46, armature 49 of relay RHS, wire 48, armature 47 of relay LHS in a raised position, wire 65, armature 66^{RH}, wire 200, coil of relay LH, wire 67, armature 54^{TR}, wire 55, armature 55^{NP}, wire 56, armature 57 of the relay XS in a raised position, wire 58, armature 59, and wires 60 and 20 to common battery terminal C. While, with relay RWS energized so that the switch is set for the traffic to the siding, the relay YS is energized when the despatcher selects the relay LHS, and we find that the relay LH is supplied with current over the same circuit as just traced to the wire 55, then along wire 61, armature 68^{RP} of the reverse relay RP, wire 69, armature 59 of relay YS, wire 58, armature 57, and wires 60 and 20 to common battery terminal C. With the relay LH once energized by either of the two above circuits, a stick circuit to common battery terminal C is provided which includes a front contact of the relay as follows: From the wire 55 along wire 61, armature 62^{KR} of the KR relay, wire 70, armature 71 in a raised position, to common battery terminal C.

The directional relays RH and LH each control controlling relays that, in turn, govern operating circuits of wayside signals. For example, the operating circuits for the signal R2a are controlled by the relay RaH and, in turn, this relay RaH is governed by the directional relay RH. Referring to Fig. 1, we find that the circuit for the relay RaH extends from battery terminal B at the right-hand end of Fig. 1 along armature 72^{LGP} of a relay LGP to be shortly described, wire 73, armature 74^{LH}, armature 75TE of a time element relay to be described later, armature 76^{KR}, armature 77^{RH} in raised position, armature 78^{RM} in down position, armature 79^{KR}, armature 80^{RAS} in down position, armature 81^{TR}, armature 82^{LAS}, wire 83, relay RaH, wire 84, armature 85 to a common battery terminal C. It is to be noted among other things that in order to energize this controlling relay RaH so as to clear signal R2a, the opposing signal L2 must be set in the stop position, the detector track circuit must be

unoccupied, the switch must be set for the main line, relay RAS must be de-energized due to a train in section R3T or section R2T, and the despatcher must select the direction of traffic from the left to the right. The relay RdH which governs the signal R2d for traffic moving from the siding to the main line, is also controlled by the directional relay RH. The circuit for relay RdH extends from the battery terminal B, shown at the right-hand end of Fig. 1, over the same circuit just traced for relay RaH up to the polar armature 79^{KR}, then with armature 79^{KR} reversed to the right-hand position, along armature 99^{TR}, armature 100^{LAS}, wire 101, relay RdH, wires 102 and 84, and armature 85 to common battery terminal C. It is to be noted, therefore, that in order to clear the signal R2d, the opposing signal L2 must be set at stop, the detector track circuit unoccupied, the switch SW reversed, and the despatcher must select the directional relay RH. The signal L2a is controlled by the controlling relay LaH which, in turn, is controlled by the directional relay LH. This time the circuit extends from the battery terminal B, shown at the right-hand end of Fig. 1, along armature 86^{RP}, armature 77^{RH}, armature 76^{KR}, armature 75TE, armature 74^{LH} of the directional relay LH, wire 87, armature 88^{LM} dropped, armature 89^{LAS} dropped, polar armature 90^{KR} in the left-hand position, armature 91^{TR}, armature 92^{RAS}, wire 93, relay LaH, wire 94, and armature 95 to common battery terminal C. Thus to clear the signal L2a, it requires that the opposing signals be set at stop, the detector track circuit unoccupied, the switch SW set normal, and the despatcher selects the directional relay LH. The signal L2b is controlled by the controlling relay LbH which is energized by a circuit that extends from the battery terminal B over the same circuit just traced for relay LaH up to the point of the polar armature 90^{KR}, then with the armature 90^{KR} reversed, to the right-hand position, along armature 96^{TR}, wire 97, relay LbH, wires 98 and 94, and armature 95 to common battery terminal C. The "call-on" signal R2c is governed by a controlling relay RcH, and this relay RcH is, in turn, controlled by a despatcher controlled relay CH. The circuit for relay RcH extends from the battery terminal B over the same circuit as traced for the relay RaH up to and including armature 80^{RAS}, and then along wire 103, armature 104^{CH}, wire 105, armature 106 of relay RcH in a down position, armature 107 in a down position, relay RcH, wires 109, 102 and 84, and armature 85 to common battery terminal C. It follows that in order to clear the "call-on" signal R2c, the despatcher must not only select the directional relay RH by energizing the relay RHS but he must, in addition, energize the relay CH. The "call-on" signal L2c is governed by a controlling

relay LCH, which has an energizing circuit which extends from battery terminal B over the same circuit as traced for the relay LaH up to and including armature 89^{LAS}, then along wire 110, armature 111 of relay CH, wire 112, armature 113, wire 114, armature 115, wire 116, coil of relay LcH, wires 117, 98 and 94, and armature 95 to common battery terminal C.

Associated with the controlling relays RaH, RcH and RdH is a relay RGP, which has an energizing circuit extending from battery terminal B, along armature 118 of relay RdH, armature 119 of relay RcH, armature 120 of relay RaH, wire 121, coil of relay RGP to common battery terminal C. This relay RGP by being energized when its associated relays are deenergized, checks the stop position of each of the R2 signals. Likewise, associated with the controlling relays LaH, LbH and LcH is a relay LGP, and a circuit for energizing this relay LGP includes an armature of each of these controlling relays in a down position as will be readily understood from the Fig. 2, and it therefore checks the stop position of signal L2.

The signal R3 is controlled by a track relay R2TR and a line relay RD. The controlling circuit for the line relay RD is not shown in the Fig. and it is to be understood that it is in accordance with well known standard practice. The control of the distant signal L3 is by a track relay L2TR and a line relay LD, and the control of this line relay LD will be in a manner similar to that used for controlling the relay RD.

For each direction of traffic there is provided an approach locking stick relay and an approach control stick relay. The approach locking stick relay RM is associated with traffic moving from the left to the right and is normally energized by a stick circuit extending from the battery terminal B located at signal R3 along armature 126 in a down position, wire 127, armature 128 of relay RGP, wire 129, armature 130 of directional relay RH, wire 136, armature 137 of the relay RM, coil of relay RM, and to common battery terminal C. Extending around the front contact of armature 137 is a shunt circuit consisting of wire 131, branching from wire 136, armature 132^{KR}, wire 133, armature 134 of the approach control relay RAS about to be described, wire 135, coil of relay RM, and to common battery terminal C, and in addition to this shunt path around the front contact of armature 137, there is a second shunt path branching from wire 131 and extending along wire 138, armature 139TE of the time element relay TE, wires 140 and 135, coil of relay RM, and to common battery terminal C. It will be noted, therefore, that the approach locking relay RM will be deenergized by the dispatcher selecting the directional relay RH, and that with relay RM once deenergized, it

can be reenergized only with the approach control relay RAS up, or in the event the time element relay TE has acted to close the armature 139TE in a manner to be described later.

Approach control stick relay RAS is normally energized by a stick circuit extending from battery terminal B, shown at the left-hand end of Fig. 1, along wire 141, armature 142 of the track relay R3TR, armature 143 of the track relay R2TR, wire 144, coil of relay RAS, wire 145, its own armature 146, and to common battery terminal C. There are provided two by-paths around the front contact of armature 146, one of which extends along wire 147, from the coil of relay RAS, armature 148 of the directional relay RH, and to common battery terminal C, while the second by-path extends from wire 147, along wire 149, a polar armature 150^{KR} of the KR relay, and to common battery terminal C. Thus, it will be observed that with a train approaching the switch SW from the left and occupying either of the track sections R3T or R2T the holding circuit for the RAS relay will be opened, and that with relay RAS once deenergized, it can be reenergized only when these track sections are vacated and the directional relay RH is down, or instead of directional relay RH being down, the switch SW is reversed so as to cause the polar armature 150^{KR} to be reversed.

Associated with traffic moving from the right to the left is an approach locking stick relay LM and an approach control stick relay LAS. The approach locking relay LM is normally energized and has an energizing stick circuit similar to that traced for the approach locking relay RM, and which extends from battery terminal B, along armature 151 of line relay LD, wire 152, armature 153 of relay LGP, wire 154, armature 155 of the directional relay LH, wire 159, its own armature 160, coil of relay LM, and to common battery terminal C. Around the front contact of armature 160 is a shunt path branching from wire 159 and extending along wire 156, armature 157 of the approach control relay LAS in raised position, wire 158, coil of relay LM, and to common battery terminal. A second by-path around the front contact of armature 160 extends from wire 159 along wire 161, armature 162TE of the time element relay TE, coil of relay LM and to common battery terminal. The approach control stick relay LAS is normally energized by a stick circuit similar to that traced for the approach relay RAS, and which starts at battery terminal B shown at the extreme right-hand end of Fig. 2, and extends along wire 163, armature 164 of the track relay L3TR, armature 165 of track relay L2TR, wire 166, coil of relay LAS, wire 167, its own armature 168, and to common battery terminal C. Around the front contact of the armature 168 is a

shunt path branching from wire 167, and extending along wire 169, armature 170 of the directional relay LH, and to common battery terminal C.

Associated with the control of the approach locking relays RM and LM is a time element relay TE. This time element relay TE may be any of the well known types and is arranged to close its contacts a predetermined time interval after its energizing circuit has been closed. Looking at Fig. 2, we find the energizing circuit for the relay TE extends from battery terminal B, along armature 171 of a relay MP, wire 172, armature 173^{TR}, armature 174^{LH}, armature 175^{RH}, coil of TE, and to common battery terminal C. Thus for the time element relay TE to function, it requires that the MP relay be energized, that the detector track section 1T be unoccupied, and that both directional relays LH and RH be down. The relay MP, which controls the supply of current to relay TE is energized by either one of two circuits. The first circuit extends from the battery terminal B, located at signal R3, along armature 126, wire 127, armature 128, wire 129, armature 130, wire 136, armature 137 in a down position, wire 176, coil of MP, and to common battery terminal C. The second circuit for energizing relay MP receives energy at battery terminal B located at signal L3 and extends along armature 151, wire 152, armature 153, wire 154, armature 155, wire 159, armature 160 in a down position, wire 177, coil of MP, and to common battery terminal C.

I will now describe the operation of the approach locking, and will assume that the dispatcher has selected the relay RHS and that energy has been supplied to the directional relay RH to lift the armature 130. Upon armature 130 being raised, the approach locking relay RM becomes deenergized opening its front contacts and closing its back contacts. It will thus be seen that, after the dispatcher has cleared the signal R2a by energizing the relay RH the approach locking relay RM is deenergized and the circuit for the switch control relay W is opened at the armature 14^{RM} of the approach locking relay RM. It follows then that it is safe for the dispatcher to select the reverse position of the switch SW by deenergizing the normal relay NWS and energizing the reverse relay RWS, in view of the fact that as long as relay RM is deenergized, since the relay W is of a type which will remain in the position to which it was last moved, the switch SW will not follow the energizing of relay RWS. The relay W will respond to the energizing of the dispatcher relay RWS only when its controlling circuit has been closed at armature 14^{RM} which can take place only when the approach locking relay RM is reenergized.

I will next assume that a train approaches signal R2 after the signal has been cleared. It is evident that if the track relay TR is momentarily short-circuited, under these conditions, so as to drop the directional relay RH, thereby permitting relay RGP to pick up, the approach locking relay RM will still remain deenergized due to its stick circuit. It follows that a momentary short circuit of the detector track section does not, with my invention, permit a loss of the approach locking.

Again it is to be noted, that after the dispatcher has selected traffic from the left to the right and energy has been supplied to the directional relay RH, then as soon as a train enters the first approach track section R3T, the circuit for the approach control stick relay RAS is opened, and the relay RAS becomes deenergized. Relay RAS will then remain deenergized even though the loss of shunt occurs on either track relay R3TR or R2TR during the time a train occupies the track sections, R3T or R2T, or in the event either relay is picked up by a foreign current. Relay RAS remains deenergized due to the fact that to reenergize the relay, the by-path around the stick armature 146 must be closed, and to close this by-path requires that the directional relay RH be deenergized so that the armature 148 is in engagement with its back contact. With relay RH deenergized and the train vacating the track sections R3T and R2T, the pick-up circuit for the relay RAS is closed and the relay restored to its normal position. With the stick relay RAS thus restored so as to close the front contact of armature 134, the relay RM is restored to its normal position. Therefore, the two stick relays RM and RAS provide a combination that continuously checks the integrity of the approach locking and insures a minimum chance of a false operation of the switch SW occurring. The approach locking relay LM and its companion relay LAS provide a continuous check on the approach locking for traffic moving from the right to the left in the same manner as relays RM and RAS provide a continuous check on the approach locking for traffic moving from the left to the right.

It is to be noted that the second by-path around the front contact of armature 146 of the relay RAS, and which by-path includes the polar armature 150^{KR} reversed to a right-hand position, provides a means for retaining the relay RAS in an energized condition whenever the switch SW is set for traffic from the siding, even though one or both of the approach track sections R3T and R2T have been occupied and then later vacated.

In the event that a route has been set up and a train has entered an approach track section of the route and it becomes necessary

to change the position of the switch before the train passes beyond the limits of the route, this can be accomplished by means of the time element relay TE and its associated relay MP. Let us assume that the despatcher has cleared signal R2a and a train has entered track section R2T traveling toward the signal and that it then becomes necessary to stop this train and to reverse the switch. The despatcher by deenergizing relay RH sets signal R2a at stop and with relay RH down, the relay MP is energized by the circuit previously pointed out and with relay MP up, the time element relay TE is energized to start its operation.

After a predetermined time interval, relay TE closes its contacts, this time interval being chosen of sufficient length that the approaching train can come to a stop to the rear of the signal R2a. With relay TE closing its contacts, the pick-up circuit for approach locking relay RM, which includes armature 139TE is closed, and the relay RM is thereby reenergized, with the result that the switch can be reversed in the usual manner. It will be understood that time element relay TE functions in a like manner for a train approaching signal L2.

Although I have herein shown and described only one form of railway traffic controlling apparatus embodying my invention, it is understood that various changes and modifications may be made therein within the scope of the appended claims without departing from the spirit and scope of my invention.

Having thus described my invention, what I claim is:

1. In combination, a railway switch, a first track section remote from the switch, a second track section adjacent to the switch, an approach control relay, a normally closed stick circuit to normally energize said relay, a track relay for said first track section to rupture the stick circuit in response to a train in said first track section, a track relay for said second track section, a traffic governing relay controlled by the track relay of the second track section arranged to be deenergized in response to a train in said second track section, a pick-up circuit for said approach control relay effective to re-energize said approach control relay when the track relay of the first track section is energized and the traffic governing relay is de-energized, and means to control the operation of the switch rendered effective with said approach control relay energized.

2. In combination, a railway switch, a first and a second approach track circuits, a detector track circuit, an approach control relay, a normally closed stick circuit for normally energizing said relay, means controlled by the first and second approach track circuits to rupture the said stick circuit in re-

sponse to a train occupying either of said approach track circuits, a pick-up circuit for said relay rendered effective to energize said relay when said first and second approach track circuits are both unoccupied by a train and the detector track circuit is occupied by a train, and means to control the operation of the switch rendered effective when the approach control relay is energized.

3. In combination, a railway switch, a directional relay which when energized permits traffic over the switch in a given direction, an approach control relay, a normally closed circuit to normally energize said approach control relay, a track circuit to open said normally closed circuit and thereby de-energize the control relay in response to a train traversing said track circuit in the direction governed by said directional relay, means active when said control relay is once deenergized to retain said relay deenergized as long as said track circuit is occupied or the said directional relay energized, and circuit means to control the operation of the switch rendered ineffective as long as said approach control relay remains deenergized.

4. In combination, a railway switch, a first relay normally energized, a second relay normally energized, a traffic governing relay to govern traffic over the switch and adapted when set to permit traffic to move over the switch to deenergize said first relay, a track circuit remote from the switch adapted when occupied to deenergize said second relay, means to prevent the reenergizing of the first relay until the second relay is energized, means to prevent the reenergizing of the second relay as long as the track circuit is occupied or the traffic governing relay set to permit traffic over the switch, and a circuit to control the operation of the switch rendered ineffective as long as the first relay remains deenergized.

5. In combination, a railway switch, a first stick relay, a normally closed stick circuit for said relay, a second stick relay, a normally closed circuit for said second relay, a traffic governing relay adapted when set to permit traffic to move over the switch to open the stick circuit for the first stick relay, a track circuit remote from the switch adapted when occupied to open the stick circuit for the second stick relay, a pick-up circuit for the first stick relay closed when the second stick relay is energized, a pick-up circuit for said second stick relay closed, when said track circuit is unoccupied and the traffic governing relay set to stop traffic, and a circuit to control the operation of the switch rendered ineffective as long as the first stick relay remains deenergized.

6. In combination, a railway switch, manual controlled relays to control the operation of the switch, a signaling means to govern traffic over the switch, a track circuit, an ap-

proach locking stick relay, a normally closed stick circuit to energize said relay, adapted to be ruptured by the signaling means cleared to permit a train to move over the switch, an approach control stick relay, a normally closed stick circuit to energize said relay and adapted to be ruptured in response to a train entering the track circuit, a pick-up circuit for the approach locking stick relay controlled by said approach control stick relay, a pick-up circuit for the approach control stick relay effective to energize said relay only after the track circuit has been vacated by the train and the signaling means set to stop traffic, and means controlled by the approach locking stick relay to render said manually controlled relays ineffective to control the switch as long as said approach locking relay remains deenergized.

7. In combination, a single track railway, a switch for said railway, a normally energized approach control relay associated with each direction of traffic over the switch, a normally closed stick circuit for each approach control relay, means responsive to a train approaching the switch to rupture the stick circuit of the approach control relay associated with the same direction of traffic as that in which the train approaches the switch, and a signaling circuit for each direction of traffic, each signaling circuit including a front contact of the approach control relay associated with the opposing direction of traffic and a back contact of the approach control relay associated with the same direction of traffic as the said signaling circuit.

8. In combination, a railway switch having a normal and a reverse position, a normal and a reverse control circuit for the switch, despatcher controlled means to selectively control said circuits, a detector track section, an approach track section, a despatcher controlled signaling circuit adapted when closed to permit traffic over said switch set in normal position, a normally energized approach locking relay deenergized in response to the closing of the signaling circuit to render ineffective the despatcher's control over the reverse control circuit of the switch, a normally energized approach control relay deenergized in response to a train entering the approach track section to retain said approach locking relay deenergized, and means rendered active by the train successively traveling through the approach and detector track sections to reenergize said approach control relay and in turn the approach locking relay to thereby restore the despatcher's control over the reverse control circuit of the switch.

9. In combination, a railway track switch, a signal for governing traffic movements in a given direction over said switch, a signal relay, a circuit including a front contact of said relay for controlling said signal, an approach locking relay, a stick circuit for said

approach locking relay including a back contact of said signal relay, an approach stick relay, a stick circuit for said approach stick relay controlled by a train approaching said signal in said given direction, a pickup circuit for said approach stick relay including a back contact of said signal relay, a pick-up circuit for said approach locking relay including a front contact of said approach stick relay, and means controlled by said approach locking relay for controlling said switch.

10. In combination, a railway track switch, a signal for governing traffic movements in a given direction over said switch, means for controlling said signal, an approach locking relay, a stick circuit for said approach locking relay closed only if said signal is controlled to indicate "stop", an approach stick relay, a stick circuit for said approach stick relay which becomes deenergized if a train approaches said signal in said given direction, a pickup circuit for said approach stick relay closed only if said signal is controlled to indicate "stop", a pickup circuit for said approach locking relay controlled by said approach stick relay, and means controlled by said approach locking relay for controlling said switch.

In testimony whereof I affix my signature.

RALPH R. KEMMERER.
